UNITED STATES PATENT OFFICE

2,532,397

BAND GROOVE SERRATING MACHINE

Morris S. Evans, Abraham O. Kleckner and Edmund A. Watson, Buffalo, N. Y., assignors to American Car and Foundry Company, New York, N. Y., a corporation of New Jersey

Application May 10, 1944, Serial No. 534,926

5 Claims. (Cl. 78—45)

1

This invention relates to a machine for placing serrations in the bottom of the band groove of shells:

The proper finishing of high explosive ammunition, particularly shells, depends on proper fastening of the rotating or driving band, which is usually made of non-ferrous material. In some instances a wavy bead is applied, cut directly into the band seat of the shell; in others a notch or serration in relatively large numbers, equally spaced around the circumference of the groove which holds the band, and parallel to the longitudinal axis of the shell, is applied. In either case special devices must be used for making the waves or serrations. The axially extending notches or serrations cannot be cut by existing machines due to the narrowness of the groove, nor can these notches be economically cut by any existing machines. It is an object, therefore, of the present invention to provide a machine for cutting axially extending serrations of equal depth and spacing throughout substantially the entire width of the shell groove bottom.

A further object of the invention is the provision of a machine for placing serrations in a shell groove by opposed tools acting in unison whereby no special holding arrangement or clamp is required for the shell.

A still further object of the invention is the provision of a machine for placing serrations in a shell groove by means of tools operated by predetermined and equal pressures.

These and other objects of the invention will be apparent to persons skilled in the art from a study of the following description and accompanying drawings, in which

Fig. 1 is a longitudinal sectional view of the improved machine;

Fig. 2 is a plan view of the machine with the shell being shown in section at the groove zone;

Fig. 3 is an enlarged side view of the indexing portion of the machine, and

Fig. 4 is a diagrammatic view showing the controls for the operation of the machine.

Referring now to the drawings in detail, it will be seen that the machine consists of a base 2 upon which is rigidly mounted two spaced apart upright plates 4, buttressed to the base by gusset members 6. The plates 4 are substantially square and are joined together by means of heavy tension rods 8 extending through the plates adjacent the corners and held in position by nuts 10 whereby any separating movement of plates 4 is prevented. Rigidly mounted upon the inner face of each plate is a heavy pan-shaped casting

2

12, having the central portion finished to provide a cylinder 14. Slidably mounted within the cylinder is a ram or piston 16 to which is bolted a plate 18, clamping in position a gasket 20. The head end of cylinder 14 has an opening bored therethrough and adapted to receive a rod 22 anchored at one end in ram or piston 16 and connected at the opposite end to a piston 24 reciprocating within a cylinder 26 anchored upon the back face of plate 4. A stuffing box or similar seal prevents leakage of pressure from cylinder 14 past rod 22, while a limiting stop 28 surrounding rod 22 insures the maintenance of a head space between the bottom of the cylinder 14 and the piston or ram carried plate 18. The thickness of stop 28 may be varied in order to limit the return motion of the ram to any desired amount. Outward motion of the ram beyond the ends of the cylinders 14 is prevented by means of a head ring 30 secured to casting 12 by stud bolts 32. This head ring prevents blowing out of the piston or ram 16 and may be utilized as a stop limiting outward motion of the ram or piston.

25 Mounted upon the machine base, intermediate plates 4, is a standard 34 having a pan-shaped depression 36 formed in the upper surface and having the rim concentric with a central bore 38. A turntable member 40 is rotatably mounted in the pan-like depression and has a stud 42 extending into the bore 38. The turntable is of itself provided with an upwardly open pan-shaped depression 44 adapted to receive the base of a shell S, as clearly shown in Fig. 1. Secured to the turntable 40 is a ratchet wheel 46 having ratchet teeth 48 formed on the periphery and of such a size as to give the proper spacing for the serrations later to be referred to.

Extending outwardly from one side of the standard 34 is a bracket 50, upon which is slidably mounted a slide member 52 having an arm 54 extending outwardly beyond the bracket. Pivotally mounted upon slide 52 is a click 56 having a tooth-engaging portion 58 adapted to engage the teeth of the ratchet wheel. The click is constantly urged into engagement with the ratchet wheel teeth by means of a flat spring 60. Rigidly mounted upon the bracket 50 is a spring urged plunger or pawl 62 adapted to cooperate with the ratchet teeth and prevent any backward motion of the ratchet wheel. Arm 54 of the slide member is pierced to receive a rod 64 adjustably connected to an arm 66 bolted or otherwise secured to one of the rams or pistons 16. Since the motion of the slide and its con-

nected arm 54 is limited so that the click may engage one tooth only of the ratchet wheel, it is necessary that a spring 68 be provided. This spring, as shown most clearly in Fig. 2, surrounds the rod 64 and has one end in engagement with an abutment 78 anchored on the rod and the other end in engagement with the pierced arm 54. In this manner the spring 68 insures movement of the slide and click sufficient to engage one tooth of the ratchet wheel while permitting excessive relative movement between rod 64 and arm 54.

The outer ends of rams or pistons 16 have secured thereto tool holding blocks 72, upon the face of which are mounted hardened knives 74. These knives are vertically adjustable with respect to the tool holders so that they may be properly positioned with respect to the groove 76 of the shell S. In cases where different diameter shells are to be serrated, the tools and tool holders may be changed as well as the turntable 40 upon which the shell rests.

As most clearly shown in Fig. 4, the cylinders 26 are connected by pipes 80 to a source of pressure, such as an air reservoir, and the pipes enter these cylinders beneath the pistons 24 so as to constantly urge the pistons outwardly and with a substantially constant pressure. It will, of course, be obvious that springs could be substituted for the fluid pressure medium, but would not give a constant pressure acting to return the rams 16. Piping 82 is connected to cylinders 14 and enter the castings 12 so as to supply pressure to the head space between the cylinder 14 and the head of ram or piston 16. The piping 82 is fed by a pipe 84 connected to a source of high pressure (not shown) and the pressure medium is controlled by a valve 86. Pressure gauge 88 is connected to pipe 84 between the control valve and cylinders 14, while a safety or relief valve 90 is also connected to pipe 84 between the valve and cylinders. The valve 86 will be of the type having a discharge port so that the supply of high pressure medium to and from cylinders 14 may be controlled. The safety or relief valve 90 will be of the adjustable type and can be so adjusted as to limit the pressure in piping 82 to a predetermined value. The pressure to be obtained in piping 82 will be selected in accordance with the exact depth of serrations 92 which it is desired to have the tools 74 cut in the shell groove 76. It will, of course, be obvious that a pressure reducing valve may be substituted for the relief valve 90, in which case it would be inserted in pipe 84 ahead of control valve 86.

In operating the machine it is only necessary that a shell having groove 76 cut therein be lowered into position on turntable 40, then the operator will open valve 86 sending high pressure into cylinders 14, forcing rams or pistons 16 outwardly. Outward movement of the rams will force tools 74 into the metal forming the bottom of the grooves 76. Since cylinders 14 are connected with relatively large diameter and short length pipes, it is obvious that tools 74 will be forced into the metal with equal pressures. Since the tools 74 act on the shell metal with equal pressure, the shell will be held centered and accordingly the mere resting of the shell on the turntable is sufficient. It is necessary that the serrations 92 be of a certain definite depth and this depth can be obtained by proper adjustment of the relief valve 90, which will limit the maximum pressure obtainable in cylinders 14. Once this maximum pressure has been determined, it is only neces-

sary to see that the tools 74 are of the same contour and remain reasonably sharp. Upon movement of the pistons 16 toward the shell the arm 66 will move and cause spring 68 to move the slide 52 as far as is permitted by bracket 50, that is, sufficient for the click 56 to engage the next adjacent tooth of the ratchet wheel 46. Continued motion of arm 66 will merely compress spring 68. As soon as the relief valve 90 functions, the operator turns off the source of pressure at valve 86 and moves it to a discharging position, permitting the pressure to be bled from cylinders 14. Bleeding of the pressure will permit the constant pressure source to move pistons 24 retracting the rams or pistons 16 and moving tools 74 out of grooves 76. During return motion of the rams, arm 66 will through rod 64 and arm 54 cause click 56 to move the ratchet wheel and connected turntable a distance equal to one tooth space. During rotation of the ratchet wheel the stop pawl 62 will be retracted and will then engage the next adjacent tooth preventing any backward rotation or shifting of the turntable. The parts of the mechanism are again in condition for a repetition of the cycle of operations just described. It will be obvious that the machine may be readily adapted to operate on different size shells by merely changing the tools and tool holders as well as the turntable and ratchet wheels in case the spacing number of serrations per shell is to be varied. Since the tools 74 must operate on the shell in direct opposition and with equal pressure, it is obvious that the shell more or less floats between the tools and the mere resting of the shell on the turntable is sufficient to insure proper placement of the serrations 92.

While the machine has been described more or less in detail, it will be obvious to persons skilled in the art that various modifications and rearrangements of parts may be made and all such modifications and rearrangements of parts are contemplated as will fall within the scope of the appended claims defining our invention.

What is claimed is:

1. In a serrating machine, a pair of opposed inner cylinders, a pair of opposed outer cylinders spaced from and horizontally aligned with said inner pair of cylinders, a piston in each of said cylinders, means rigidly connecting the pistons of the inner pair of cylinders with the pistons of the outer pair of cylinders, opposed serrating tools carried by the pistons of the inner pair of opposed cylinders, a horizontal turntable for supporting the object to be serrated located intermediate the opposed serrating tools, a source of controlled high pressure connected with said inner pair of cylinders for moving the pistons therein to advance the opposed serrating tools in unison to impress serrations upon the object, and a source of continuous relatively lower pressure connected with said outer pair of cylinders acting against the pistons therein to constantly urge the serrating tools toward retracted position.

2. In a serrating machine, a pair of opposed inner cylinders, a pair of opposed outer cylinders spaced from and horizontally aligned with said inner pair of cylinders, a piston in each of said cylinders, means rigidly connecting the pistons of the inner pair of cylinders with the pistons of the outer pair of cylinders, opposed serrating tools carried by the pistons of the inner pair of opposed cylinders, a horizontal turntable for supporting the object to be serrated located intermediate the opposed serrating tools, a source

of controlled high pressure connected with said inner pair of cylinders for moving the pistons therein to advance said opposed serrating tools in unison to impress serrations upon the object, a source of continuous relatively lower pressure connected with said outer pair of cylinders acting against the pistons therein to constantly urge the serrating tools toward retracted position, means mounted at a side of the machine for rotating the turntable a predetermined amount in one direction, and means carried by the piston of one of said inner cylinders connected with and adapted to operate said turntable rotating means during retracting movement of the serrating tools.

3. In a serrating machine, opposed reciprocable serrating tools, a standard located intermediate the opposed serrating tools, a horizontal turntable for supporting the object to be serrated mounted on the standard, means for advancing the opposed serrating tools in unison to impress serrations upon the object, means constantly urging the serrating tools toward retracted position, a ratchet wheel fixed around the periphery of the turntable, a bracket extending from the standard adjacent said ratchet wheel, a slide member mounted on the bracket, a spring-pressed click pivotally connected to the slide member and engaging said ratchet wheel for rotation of the turntable a predetermined amount in one direction, and means including an arm secured to one of the serrating tools operatively connected with the slide member for actuating the click to rotate the turntable during retraction of the serrating tools.

4. In a serrating machine, a pair of opposed inner cylinders, a pair of opposed outer cylinders spaced from and horizontally aligned with said inner pair of cylinders, a piston in each of said cylinders, means rigidly connecting the pistons of the inner pair of cylinders with the pistons of the outer pair of cylinders, opposed serrating tools carried by the pistons of the inner pair of opposed cylinders, a standard located intermediate the opposed serrating tools, a horizontal turntable for supporting the object to be serrated mounted on said standard, a source of controlled high pressure connected with said inner pair of cylinders for moving the pistons therein to advance the serrating tools in unison to impress serrations upon the object, a source of continuous relatively lower pressure connected with said outer pair of cylinders acting against the pistons therein to constantly urge the serrating tools toward retracted position, a ratchet wheel fixed around the periphery of the turntable, a bracket extending from said standard adjacent the ratchet wheel, a slide member mounted on the bracket, a spring-pressed click pivotally connected to the slide member and engaging said

ratchet wheel for rotation of the turntable a predetermined amount in one direction, and means including an arm secured to the piston of one of the inner cylinders operatively connected with the slide member for actuating the click to rotate the turntable during retraction of the serrating tools.

5. In a serrating machine, opposed reciprocable serrating tools, a standard located intermediate the opposed serrating tools, a horizontal turntable for supporting the object to be serrated mounted on the standard, means for advancing the opposed serrating tools in unison to impress serrations upon the object, means constantly urging the serrating tools toward retracted position, a ratchet wheel fixed around the periphery of the turntable, a bracket extending from the standard adjacent said ratchet wheel, a slide member mounted on the bracket, a spring-pressed click pivotally connected to the slide member and engaging said ratchet wheel for rotation of the turntable a predetermined amount in one direction, and arm extending laterally from one of the serrating tools, and a rod adjustably connected at one end with the end of said arm and having a lost motion connection at its other end with the slide member for actuating the click to rotate said turntable during retraction of the serrating tools.
